DESIGN FOR A PIPE-LINE CONTROL FITTING

Leland S. Hamer, Long Beach, Calif.

Application January 17, 1944, Serial No. 112,253

Term of patent 14 years

(Cl. D91—1)

To all whom it may concern:

Be it known that I, Leland S. Hamer, a citizen of the United States, residing in the city of Long Beach, county of Los Angeles, and State of California, have invented a new, original, and ornamental Design for a Pipe-Line Control Fitting, of which the following is a specification, reference being had to the accompanying drawing, forming a part thereof.

Fig. 1 is a perspective view of the pipe-line

control fitting taken from one side, showing my design. Fig. 2 is a perspective view of the fitting taken from the opposite side, and Fig. 3 is a perspective view of the fitting taken from the right end of Fig. 2.

I claim:

The ornamental design for a pipe-line control fitting, as shown.

LELAND S. HAMER.
